UNITED STATES PATENT OFFICE.

GEORGE D. POGUE, OF ST. LOUIS, MISSOURI.

LIQUID-FUEL PUMP.

1,250,651.

Specification of Letters Patent. Patented Dec. 18, 1917.

Original application filed July 19, 1915, Serial No. 40,678. Divided and this application filed February 11, 1916. Serial No. 77,629.

To all whom it may concern:

Be it known that I, GEORGE D. POGUE, a citizen of the United States, residing at St. Louis, Missouri, have invented a certain new and useful Improvement in Liquid-Fuel Pumps, of which the following is a full, clear, and exact description, such as will enable others skilled in the art to which it appertains to make and use the same.

10 This application is a division of my pending application Serial No. 40,678, filed July 19, 1915, for variable feed pumps.

15 The invention described in the present application consists in a liquid fuel pump in which the valves are of a novel construction that facilitates the removal of same and also enables the passageway between the inlet and outlet valves to be drained without removing the valves.

20 Figure 1 of the drawings is a transverse sectional view, illustrating one cylinder of the pump and the valves that coöperate with said cylinder.

Fig. 2 is a front elevational view, partly in vertical section, of the cylinder casting or body portion of the pump in which the cylinders are formed; and

Fig. 3 is a horizontal sectional view, taken on approximately the line 3—3 of Fig. 2.

25 Referring to the drawings, which illustrate the preferred form of my invention, 22 designates the cylinder casting or body portion of the pump in which the cylinders B are formed, the pump comprising three cylinders and three plungers A that reciprocate in said cylinders. Each cylinder is provided with an inlet valve 1 and one or more discharge valves 2 which are so designed that the valves of any cylinder can be removed 30 easily without cutting the other cylinders of the pump out of operation. Said valves are also so constructed that the passageway between the inlet and discharge valves of any cylinder can be drained without removing the valves. The valves 1 and 2, which are of ball type, are arranged in vertical alinement with each other, preferably in front of the cylinder B with which they coöperate, in a vertically-disposed hole or opening in the member 22. The upper end of the opening in the member 22, in which the valves of one cylinder are arranged, is closed by a removable cap 24, and the lower end of said opening is closed by a removable cap 25 which

carries a manually-operated valve 26. The 55 inlet valve 1 is provided with a cage 1^a that is screwed into the member 22 and the discharge valves 2 are both provided with separate cages 2^a, the bottom one being seated in a pocket in the member 22 and the top one 60 being screwed into the member 22. The inlet and discharge valves of all of the cylinders are arranged in transverse alinement with each other, preferably in front of the cylinders, and a supply pipe 27 leads to a 65 channel 28 in the member 22 that is common to all of the cylinders, or, in other words, which supplies the fuel or other liquid being pumped to all of the cylinders. A duct 29 leads from each of the cylinders B to the 70 passageway between the inlet and discharge valves of said cylinder and at the lower end of said duct is a removable closure 29^a, as shown in Fig. 1, that enables said duct and cylinder to be cleaned. Horizontally-disposed discharge ducts 28^a that are formed in the member 22 between the cylinders B, as shown in Fig. 3, lead from the discharge valves of the respective cylinders to discharge pipes 28^b. The manually-operated 75 valve 26 previously mentioned is provided with a stem which is so constructed that when it is screwed upwardly into the position shown in Fig. 1 no fuel can pass from the channel 28 into the particular cylinder 80 with which said valve 26 coöperates. The stem of said valve 26 is provided at its upper end with an extension 26^a, shown in Fig. 1, that unseats the inlet valve 1 when said valve 26 is closed, and thus permits the contents 85 of the passageway between the inlet and discharge valves to escape through a duct 26^b that is formed in the stem of said valve, the valve 26 being provided with a pet cock or other suitable device 26^c, that controls the 90 duct in the stem of the valve. If it is desired to examine or clean the valves of a certain cylinder, this can be accomplished without cutting the other cylinders out of operation by merely closing the valve 26, so as to 95 cut off the supply of fuel to that particular cylinder, and if it is desired to drain the passageway between the inlet and discharge valves of a certain cylinder without removing said valves, this can be effected by 100 merely closing the valve 26 and opening the pet cock 26^c at the lower end of said valves, so as to permit the contents of said passageway 105

way to escape through the hollow stem of the valve. A pump provided with valves of the construction and arrangement above described can be manufactured at a low cost; 5 it is very compact; the discharge pipes can be arranged conveniently and the valves of any cylinder can be removed or inspected without stopping the pump or the machine that the pump is supplying the liquid to; 10 thus making the pump particularly adapted for use with an internal combustion engine, owing to the fact that it is not necessary to stop the engine when one cylinder of the pump gets out of order.

15 Having thus described my invention, what I claim, and desire to secure by Letters Patent, is:

1. A multi-cylinder pump provided with a member in which all of the cylinders are 20 formed, inlet and discharge valves for said cylinders arranged in said member in transverse alignment with each other at one side of the cylinders, and discharge ducts in said member arranged between the cylinders and leading from the discharge valves.

2. A fuel pump having a body portion formed from a block of metal provided with a plunger cylinder, said block having an opening that extends clear through 30 same, inlet and discharge valves arranged in separate cages in said opening, a liquid fuel supply duct formed in said block, and removable closures for the opposite ends of said opening arranged on the top and bottom faces of said block.

3. A multi-cylinder pump, comprising a plurality of cylinders, each of which is provided with separate inlet and discharge valves, means for supplying liquid to said 40 inlet valves and means whereby the supply to any cylinder can be cut off without affecting the supply to the other cylinders of the pump.

4. A plunger pump provided with a cylinder, a passageway communicating with said cylinder and equipped with inlet and discharge valves, a manually-operable device for cutting off said passageway from the supply line and for unseating said inlet 50 valve, and means on said device for enabling

said passageway to be drained when said passageway is cut off from the supply line.

5. A plunger pump provided with a cylinder, a passageway equipped with inlet and discharge valves, a duct leading from said 55 passageway to said cylinder, means for enabling said duct to be cleaned out without disturbing said valves, a device for cutting off the supply line from said passageway and for unseating the inlet valve, and means 60 for enabling said passageway to be drained when the supply line is cut off from same.

6. A plunger pump, comprising a body portion provided with a cylinder, an opening of varying diameter extending clear 65 through said body portion, an inlet valve in said opening, a plurality of discharge valves provided with cages of different diameters that are arranged in said opening, one above the other, and closures for the opposite ends of said opening.

7. A plunger pump provided with an inlet valve and a discharge valve that operate automatically when the pump is in use, a manually-operated valve for cutting off the 75 supply to the pump cylinder, said valve having a hollow stem and a portion that unseats the inlet valve when the supply to the pump cylinder is cut off, and a closure for the hollow stem of said valve.

8. A multi-cylinder pump, comprising a member that is provided with a plurality of cylinders, said member having a plurality of openings that are arranged in transverse alignment with each other at one side 85 of said cylinders, inlet valves and discharge valves in said openings for the respective cylinders, a supply channel in said member that is common to all of said valve openings, and discharge ducts in said member 90 arranged between the pump cylinders and leading from the discharge valves of the various cylinders.

In testimony whereof I hereunto affix my signature in the presence of two witnesses, this seventh day of February, 1916.

GEORGE D. POGUE.
